KEG WASHING APPARATUS

Grant F. Barrett, Spokane, Wash., assignor to
General Machinery Co., Spokane, Wash.

Application December 8, 1947, Serial No. 790,349

1 Claim. (Cl. 134—43)

1

This invention relates to a beer keg washer and it is one object of the invention to provide a washer of this character of such construction that kegs may be fed to the front end of the apparatus and then transferred in step by step movements into position for spraying of caustic cleansing fluid into the kegs and then into position for discharge of rinsing water into the kegs, after which the kegs being removed from the washing apparatus.

Another object of the invention is to provide a keg washing apparatus wherein kegs are deposited at the front end of a frame and then turned to such a position that their bung holes are disposed at the bottoms of the kegs, the kegs being then automatically transferred to a location for discharge of the cleansing fluid through their bung holes into the kegs and then transferred to a position for discharge of rinsing water into the kegs.

Another object of the invention is to provide a keg washing apparatus having a frame provided with saddles or seats to receive and support the kegs with nozzles extending into the kegs through their bung holes, the nozzles or spray heads being mounted upright at ends of pipes and flow of liquid through the pipes being controlled by valves having operating levers so associated with the nozzles or spray heads that as kegs are set in place over the said nozzles, they will rest upon the levers and automatically cause the valves to be opened and held open until the kegs are lifted out of contact with the levers.

Another object of the invention is to provide a keg washing apparatus having at its front end a device tiltable downwardly as a keg to be washed is set in place at the front end of the frame and carrying a finger or peg for engaging through the bung hole of the keg and automatically stopping rotation of the keg when its bung hole is at the bottom of the keg.

Another object of the invention is to provide a keg washing apparatus wherein a series of kegs are moved at the same time from one position to another towards the rear end of the frame during a cleaning operation.

Another object of the invention is to provide a keg cleaning apparatus, which is strong and durable, rapid in its operation and very efficient as the kegs are thoroughly cleansed with caustic cleansing liquid and then thoroughly rinsed with clear water so that all of the caustic will be removed from the kegs, the caustic being returned to a container so that it will not be wasted and may be again withdrawn from the container and

2

forced by a pump through a pipe to discharge nozzles.

The invention is illustrated in the accompanying drawings wherein:

5 Fig. 1 is a top plan view of the improved keg cleaning apparatus.

Fig. 2 is a view showing a portion of the keg cleaner in side elevation.

Fig. 3 is a fragmentary sectional view upon 10 an enlarged scale taken vertically along the line 3—3 of Figure 1.

Fig. 4 is an enlarged view of one of the spray heads or nozzles together with a portion of the pipe carrying the same and a valve for controlling flow of liquid through the pipe.

Fig. 5 is a view of the device for holding a keg in position with its bung hole at its bottom preparatory to transfer of the keg to a position over a spray nozzle.

20 This improved keg cleaning or washing apparatus has a frame 1, which may be supported in an elevated position in any desired manner and longitudinally of which extend bars 2 spaced from each other transversely of the frame. The 25 bars 2 project from the front end of the frame and since their front end portions project quite a distance from the frame they are supported by props 3. Bearing blocks 4 extend upwardly from the bars 2 near front ends thereof, and carry 30 shafts 5 and 6 upon which wheels or rollers 7 and 8 are mounted, the rollers 7 being idler rollers and the rollers 8 being fixed to the shaft to turn therewith and constituting means for imparting turning motion to a keg K, set in place upon the 35 companion rollers 7 and 8 and supported thereby as indicated by dotted lines in Figure 2. Spaced from opposite sides of the bar are guides 9 which are formed of angle metal and are supported above the rollers 7 so that a keg K may be fed onto the guides and roll therefrom onto the rollers. The kegs may be fed to the guides by a suitable conveyor (not shown) or manually placed upon the guides by a workman. A sprocket wheel 10 about which a chain 11 is trained is 40 mounted upon the shaft 6, so that rotary motion may be imparted to this shaft and to the rollers 8 and as the rollers 8 rotate they impart turning motion to the keg.

45 The keg is to be brought to a stop with its bung hole at its bottom and in order to do so there has been provided an arm 12 which extends across the shaft 5 and is pivotally mounted for vertical tilting movement by a yoke 13, a vertical pin or peg 14 being mounted through the rear 50 end portion of this arm. The forward portion of

the arm is weighted by a sleeve 15 secured about it and therefore the rear end portion of the arm will be urged upwardly and the upper end of the peg or finger 14 have contact with a keg set at rest upon the rollers. As the keg is turned its bung hole will be shifted downwardly into position under the keg and when the bung hole reaches the finger the arm will be tilted vertically and the finger pass upwardly through the bung hole into the keg and prevent further rotation of the keg. The rollers 8 will continue to rotate and have rubbing contact with the keg but the idler rollers 7 will cease to turn when rotation of the keg stops.

The keg is then to be shifted in step by step movements along the frame into place upon saddles which may be referred to as washing stations 16 and 17, and rinsing stations 18 and 19, and are formed by blocks 20 rising from the bars 2 and arranged in pairs spaced from each other longitudinally of the bars and having upper ends cut diagonally in downwardly converging relation to each other so that the barrels will rest in stationary position upon these blocks. In order to move the kegs from the rollers in step by step movements to the various washing and rinsing stations there has been provided a carriage 21 having longitudinally extending bars 22 carrying sets of upwardly extending blocks 23 cut diagonally at their upper ends the same as the blocks 20 and forming saddles spaced from each other longitudinally of the bars 22. End portions 22' of the bars 22 are formed separate therefrom and secured to them by bridging bars 24 and providing spaces 25 near opposite ends of the side bars of the carriage 21. Shafts 26 extend across front and rear portions of the bars and are rotatably mounted through bearings 27 carried by these bars and have end portions projecting outwardly from the bars 2 for carrying arms 28 which are firmly secured to these shafts so that as the shafts rotate the arms will be swung in circular paths about the shafts as indicated by the circular line of dashes and arrows in Figure 2. During this swinging movement of the arms the carriage will be shifted upwardly and downwardly and also longitudinally due to the fact that outer ends of the arms 28 are pivoted to the end sections 22' of the bars 22 but the carriage will at all times remain in a horizontal position and kegs resting upon saddles formed by the blocks 23 will remain in place upon these saddles and not roll off of them. The openings or spaces 25 are provided so that during movement of the carriage ends of the shafts 26 may pass through these spaces and not strike the side bars of the carriage and interfere with movement of the carriage. Large sprocket wheels 29 are firmly mounted upon the shafts 26 and about these sprockets are trained chains 30 which extend downwardly therefrom and have their lower portions trained about small sprocket wheels 31 firmly mounted upon shafts 32 and 33 which project laterally from inner side portions of gear reduction boxes 34 and 35 located near front and rear ends of the main frame of the washing apparatus. The gearing in the box 34 is driven from a motor 36, rotation is transmitted from gearing in the box 34 to gearing in the box 35 by a transmission shaft 37 so that the shafts 32 and 33 are simultaneously rotated. The shaft 32 also carries a sprocket wheel 38 about which is trained the chain 11 which extends upwardly therefrom and has its upper portion trained about the sprocket 10 and causes rotation to be

imparted to the shaft 6 about the rollers or wheels 8 carried thereby.

During rotation of the shafts 26, the carriage will be swung upwardly from a lowered position 5 under the bars 2 and a keg resting upon the rollers 7 and 8 will be lifted by the saddle blocks at the front end carriage and carried upwardly and then rearwardly and downwardly and deposited upon the saddle blocks forming the first washing station 16. The carriage continues its downward movement and then moves forwardly and upwardly to remove another keg from the rollers while at this time the second set of saddle blocks carried by the carriage lifts the previously deposited keg from the first washing station and transfers it to the second washing station. This is repeated and the kegs progressively transferred in step by step movement to the first and second washing stations 16 and 17 and then to the rinsing stations 18 and 19, the washed and rinsed keg being removed from the second rinsing station by the final set of saddle blocks 23, carried by the carriage and deposited in a suitable conveyance or upon a conveyor leading from the washing apparatus and not shown in the drawings.

The kegs are washed by caustic, or other suitable cleaning fluid, and this fluid is stored in a tank 39 with which a pump 40 is connected by a pipe 41 so that the caustic washing fluid may be withdrawn from the tank by the pump and forced under pressure through a pipe 42 which extends into the main frame of the washing apparatus and then upwardly therein midway its 35 width. The upper end of the pipe 42 carries a T-coupling 43 located between the bars 2 midway the length of space between the saddles or washing stations 16 and 17 and from this coupling extend pipes 44. The pipes 44 extend longitudinally of the frame in opposite directions and have their outer ends connected with upstanding tubular spray heads or nozzles 45 by couplings 46, the nozzles being closed at their upper ends by rounded heads, as shown in Figure 4, and being formed through their heads and their side 40 walls with a multiplicity of perforations 47 through which the caustic cleaning fluid is discharged in jets. The nozzles pass upwardly through the bung holes of the kegs as the kegs settle upon the saddle blocks 20 at the two cleaning stations and as a barrel settles in place it makes contact with the forked end or yoke 48 of a lever 49 and depresses the lever so that the lever which is pivoted to an upstanding post 50 of a valve 51 will apply downward pressure to the stem 52 of a valve head 53 and cause opening of the valve. Discharge of the cleaning fluid will continue as long as the keg rests upon the saddle blocks and fluid which flows from a barrel during a cleaning operation returns to the tank. Splash plates 54 extend upwardly at an incline from ends of the tank for guiding cleaning fluid back into the tank and one of these 55 splash plates has an extention serving as a shield for the sprocket 29 and the chain 30.

After the barrel has been thoroughly sprayed with cleaning fluid at the two washing stations and thus thoroughly cleaned, it is transferred to the rinsing stations 18 and 19 where it rests upon their saddle blocks. In order to supply rinsing water there has been provided a pipe 56 which leads from a water main or other source of water under pressure and has a portion extending vertically under the main frame similar to the manner in which the pipe 42 extends upwardly. The

upper end of this pipe 56 is connected with pipes 57 by a T-coupling 58 and at their outer ends the pipes 57 carry upstanding nozzles 59 corresponding to the nozzles 45. Flow of water through the pipes 57 and their nozzles 59 is controlled by valves 60 which are of the same construction as the valves 51 and these valves are opened by levers 61 when kegs are resting upon the levers and seated upon the saddle blocks of the rinsing stations. It will thus be seen that during use of the keg washing apparatus kegs will be moved in step by step movements from the rollers 7 and 8 to the two washing stations where the nozzles 45 enter the kegs through their bung holes and spray caustic cleansing solution into the kegs and are then shifted in step by step movements to the two rinsing stations where the nozzles 59 enter the kegs and clear water is discharged into the kegs. The kegs will thus be thoroughly washed and rinsed and subjected to two washings and two rinsings, after which the kegs are automatically removed from the second rinsing station by the blocks 23 at the rear end of the carriage and placed in a vehicle or onto a conveyor by means of which they are transported to a place of storage or to a filling apparatus.

Having thus described the invention, what is claimed is:

A keg washing apparatus comprising a frame supported horizontally in an elevated position and including bars projecting from front and rear ends of the frame and spaced transversely from each other, front and rear shafts rotatably mounted across said bars transversely thereof adjacent ends of said frame, front and rear rollers spaced from each other longitudinally of the forwardly projecting portions of said bars

and constituting a keg-receiving station, a member between said rollers adapted to engage in a bung hole of a keg and hold the keg stationary with its bung hole presented downwardly, arms carried by and extending from said shafts radially thereof and having swinging movement in circular paths intermediate the width of said frame during rotation of the shafts, a carriage midway the width of said frame having spaced side bars pivoted at their ends to outer ends of said arms and having movement vertically through the frame and longitudinally thereof during swinging movement of the arms, saddles spaced from each other longitudinally of said frame and constituting a washing station and a rinsing station, mechanisms located at the washing and rinsing stations for discharging liquid upwardly through their bung holes into kegs resting upon the saddles, saddles carried by said carriage in position for engaging under kegs and transferring the kegs in step by step movements from one station to another during movement of the carriage, a motor, a shaft rotated from said motor, and means for transmitting rotary motion from the last mentioned shaft to the rollers and to the shafts carrying said arms.
